US00D993492S

(12) **United States Design Patent** (10) Patent No.: **US D993,492 S**
 McGee et al. (45) Date of Patent: ** Jul. 25, 2023

(54) **LIGHTING FIXTURE**

(71) Applicant: **Wangs Alliance Corporation**, Port Washington, NY (US)
 (72) Inventors: **Molly McGee**, Tiverton, RI (US);
Robert De'Armond, Jr., Temecula, CA (US)

(73) Assignee: **WANGS ALLIANCE CORPORATION**, Port Washington, NY (US)

(**) Term: **15 Years**

(21) Appl. No.: **29/868,438**

(22) Filed: **Dec. 2, 2022**

(51) LOC (14) Cl. **26-05**

(52) U.S. Cl.

USPC **D26/88**; D26/90

(57) **CLAIM**

The ornamental design for a lighting fixture, as shown and described.

DESCRIPTION

FIG. 1 is a front right perspective view from above of a lighting fixture according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the lighting fixture that form no part of the claimed design.

1 Claim, 7 Drawing Sheets
